DESIGN FOR DOOR-KNOBS.

Specification forming part of Design No. **11,226**, dated June 3, 1879; application filed May 10, 1879.
[Term of patent 7 years.]

UNITED STATES PATENT OFFICE

RODOLPHE CHRISTESEN, OF HARTFORD, ASSIGNOR TO THE RUSSELL & ERWIN MANUFACTURING COMPANY, OF NEW BRITAIN, CONN.

DESIGN FOR DOOR-KNOBS.

Specification forming part of Design No. **11,226**, dated June 3, 1879; application filed May 10, 1879.

[Term of patent 7 years.]

To all whom it may concern:

Be it known that I, RODOLPHE CHRISTESEN, of the city and county of Hartford, and State of Connecticut, have invented a new and useful Design for Door-Knobs; and I do hereby declare that the following specification, taken in connection with the accompanying photographic illustration, forming a part of the same, is a full, clear, and exact description thereof.

The novel design hereinafter described is adapted to the face of a door-knob, and possesses the characteristic feature of being in the Japanese style of ornament.

As shown in the accompanying illustration, the face of the knob is surrounded by a raised band, *a*, which is intersected by an ornamental diagonal band, *b*, extending across a portion of the face of the knob. The space between

the bands *a* *b* is occupied by a section of diaper ornament, *c*, composed of rectangular figures, and oppositely located on the face of the knob and extending to its edge is a section of fish-scale or tile ornament, *d*. The central portion of the face is ornamented by a shrub, *e*, bearing leaves and flowers, and by two birds, *f*, upon a mottled ground.

The design may be cast in relief or engraved, and is adapted to a knob having a convex, flat, or a concave face.

What I claim, and desire to secure by Letters Patent, is—

The Japanese design for the face of a door-knob, substantially as described and shown.

RODOLPHE CHRISTESEN.
